PUMP

Application filed September 21, 1927. Serial No. 220,875.

This invention relates to improvements in pumps.

One of the objects of my invention is in a centrifugal pump to enable the application of primary power and to provide between the axis of the device and the point of the application of the power a leverage equal to the length of the radius of the pump casing.

Another object of the invention is in a device of the character specified to avoid the use of centrally located shafts for the application of power which increases the power necessary to rotate the device.

Still another object of the invention is to utilize the combined action of centrifugal force due to the rotation of a casing in combination with impelling means for rotating the hydraulic medium in the opposite direction to increase the lifting action of the centrifugal force applied to the casing and thus cause it to rise more rapidly in the pipes carried thereby.

Still another object of this invention is to provide means for guiding and enclosing or confining particles of the hydraulic medium acted upon by centrifugal action due to rotation of a casing and I preferably provide around the edge of a rotating casing which dips into the hydraulic medium a series of pipes of sufficient diameter to enclose and guide the major portion of the particles of water which the rotation of the casing at a given speed is capable of elevating and such particles of water within the pipes are thus, instead of being loosely raised within a large casing, confined and subjected to centrifugal pressure due to rotation of the casing and a particle will have a planetary motion in the pipes because it will tend to rotate about the center of rotation of the casing, the force being continuously applied to the particles in each of the confined columns of water in the pipes, and will also tend to rotate about the axis of the pipe or column of water, so that any such particle will be caused to be elevated more rapidly than water which is unconfined. I also preferably arrange these pipes in inclined position in relation to the vertical axis of the device so as to facilitate

the guiding of the confined water or other liquid medium.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a view in vertical section substantially through the axis of the device showing a preferred embodiment of my invention; and

Fig. 2 is a plan view of the device shown in Fig. 1.

Referring now to these drawings, which illustrate a preferred embodiment of my invention, C is a conical casing open at its lower end c and divided into an upper section 1 and intermediate section 2 and lower section 3, and having mounted therein two sets of pipes 4 and 5 respectively, one set of which has the lower ends of the pipes extending through the open end c of the casing and has the upper ends extending into the intermediate section 2, the said pipes 4 being arranged to dip at their lower open ends into a body of water W and terminating at their upper open ends within the intermediate compartment 2 so as to discharge any water passing through such pipes thereinto. These pipes 4 are preferably arranged in a position inclined in relation to the vertical axis of the device, the incline being disposed in the direction of rotation thereof, so that when the casing is rotated centrifugal action will cause water to rise within the pipes 4 and be discharged within the intermediate section 2, from which such water is again elevated by the centrifugal action of the casing through the pipes 5 and discharged into the gutter 6 from which it is carried through a suitable channel 7.

In order to procure the most efficient operation of centrifugal force, the casing C is rotated at a high rate of speed, and in accordance with my invention I am enabled to rotate this casing with a minimum of power. Obviously if power is applied at the center

or axis we would be unable to obtain the benefit of any leverage in the application of such power while if primary power be applied to the outer perimeter of the casing with the axis acting as the pivot, we are enabled to procure the benefit of the leverage between the point of application on the outside and the axis and in order so to take advantage of this leverage, I apply my primary propelling force at the outer edge or periphery of the casing and preferably utilize, for the purpose, an air propeller 10 mounted upon a bracket 11 at the top of the casing, and the casing is preferably supported by a frame F 15 reinforced by struts S and provided with a track bar T which cooperates with a track bar T' on the casing and between which track bars I insert a plurality of balls so as to produce a ball bearing support for the upper 20 end of the casing. The lower end of the casing is steadied and partially supported by the use of an annular track bar T^a on the casing, which is provided with a flange t adapted to enter or fit between grooves g in 25 rollers R supported in bearings B which are in turn mounted on brackets B' attached to the frame members F. Current is supplied to members 10' mounted adjacent to the air propellers by any suitable means, and as 30 shown, the current is carried through the leads L to brushes b which engage rails r carried in a channel bar C' mounted on the casing, leads L' being taken off from these brushes to the motor and thus providing 35 leads which rotate with the casing and motor. In operation the motor is started in any suitable manner which causes the air propellers to rotate and move in a circular path through the air, acting, as aforesaid, through 40 a leverage which is equal to the radius of the casing.

It will be understood that the elevation of water is greatly assisted by the combination of forces utilized in the intermediate 45 tank, namely, the centrifugal force, due to the rotation of the casing and the movement in the opposite direction of the medium by an impeller I or other suitable mechanism. The impeller I is a conventional water-impelling device such as heretofore commonly 50 used and described under the name "impeller" in various standard text books. The function of the impeller I is to impart an impelling force to the body of water in the 55 intermediate tank by giving it centrifugal motion, in such an upward direction that will impel the water into the pipes and thus assist in raising the liquid in said pipes. This is accomplished by continually sending a high 60 crest wave toward the mouths of the pipes which practically rams the water inside them by force.

Having described my invention, I claim:—

1. A pump embodying a casing supported 65 for rotation and having an open end dipping

within a body of liquid, and means for applying primary power to the periphery of the casing for rotating said casing to elevate the water therein applied to the periphery of the casing, said power means comprising an air propeller mounted on the outer wall of said casing, and means for rotating said propeller. 70

2. A centrifugal pump embodying a casing open at its lower end and dipping within a body of liquid, a series of pipes arranged around the inner surface of said casing, and means for rotating said casing to elevate water within said pipes, said means comprising an air propeller mounted on the outer wall of said casing, and means for rotating said propeller. 80

3. A pump embodying a casing supported for rotation and having an open end dipping within a body of liquid, means for rotating said casing to elevate the water therein, and a liquid impeller rotatably mounted within said casing, and power means for rotating the same to assist the centrifugal action due to the rotation of the casing in the raising 85 of the liquid. 90

4. A centrifugal pump embodying a casing open at its lower end and dipping within a body of liquid, a series of pipes arranged around the inner surface of said casing, means for applying primary power at the outer periphery of the casing to elevate water within said pipes, a liquid impeller rotatably mounted within said casing, and power means for rotating the same to assist the centrifugal action due to the rotation of the casing in the 100 raising of the liquid. 100

5. A centrifugal pump embodying a casing open at its lower end and dipping within a body of liquid, a series of pipes arranged around the inner surface of said casing, means for applying primary power at the outer periphery of the casing to elevate water within said pipes, said power means comprising an air propeller mounted on the outer wall of said casing, means for rotating said propeller, and a liquid impeller rotatably mounted within said casing, and power means for rotating the same to assist the centrifugal action due to the rotation of the casing in the 110 raising of the liquid. 110

6. In a centrifugal pump in combination with a casing open at its lower end and supported to cause rotation of said lower end within a body of liquid, a series of pipes arranged around the inner surface of said casing, an air propeller mounted on the outer surface of said casing, power means for operating said propeller to rotate the casing about its axis, impelling means rotatably mounted centrally of said pipes to assist in elevating the water within the same, and means for discharging water from said pipes. 120 115

7. In a centrifugal pump in combination with a casing open at its lower end and supported to cause rotation of said lower end 125 130

within a body of liquid, a series of pipes arranged in positions inclined in relation to the vertical axis of the device, an air propeller mounted on the outer surface of said casing, power means for operating said propeller to rotate the casing about its axis, impelling means rotatably mounted centrally of said pipes to assist in elevating the water within the same, and means for discharging water from said pipes.

8. In a centrifugal pump in combination with a casing open at its lower end and supported to cause rotation of said lower end within a body of liquid, a series of pipes arranged in positions inclined in relation to the vertical axis of the device, an air propeller mounted on the outer surface of said casing, power means for operating said propeller to rotate the casing about its axis, impelling means rotatably mounted centrally of said pipes to assist in elevating the water within the same, means for discharging water from said pipes, said casing being divided into a plurality of sections, one of which has pipe terminals for the discharge of water therein and re-elevation of water therefrom.

In witness whereof, I have signed my name to the foregoing specification.

ISAAC SCHAFRAN.
